[57] CLAIM

The ornamental design for a lighted magnifier-flashlight, as shown and described.

DESCRIPTION

FIG. 1 is a top, front and right side isometric view of a lighted magnifier-flashlight, showing my new design;
FIG. 2 is a top plan view thereof;
FIG. 3 is a left side elevational view thereof;
FIG. 4 is a front elevational view thereof;
FIG. 5 is a rear elevational view thereof;
FIG. 6 is a bottom plan view thereof;
FIG. 7 is a right side elevational view thereof; and,
FIG. 8 is a top, front and left side isometric view showing the lighted magnifier-flashlight with its magnifier portion shown in an extended position.
